UNITED STATES PATENT OFFICE.

GOMER LEWIS, OF UNIONTOWN, PENNSYLVANIA.

RAIL-JOINT.

No. 915,196.

Specification of Letters Patent. Patented March 16, 1909.

Application filed June 29, 1908. Serial No. 440,907.

To all whom it may concern:

Be it known that I, GOMER LEWIS, a citizen of the United States, residing at Uniontown, in the county of Fayette and State of Pennsylvania, have invented a new and useful Rail-Joint; and I do hereby declare the following to be a full, clear, and exact description of the invention, such as will enable others skilled in the art to which it

10 appertains to make and use the same.

The invention relates to improvements in rail-joints, and has for its object to provide a simple, inexpensive and efficient device of this character adapted for use in railroads and mine roads.

With these and other objects in view, the invention consists in the novel construction and arrangement of parts hereinafter described and shown and particularly pointed 20 out in the appended claim.

In the drawings: Figure 1 is a plan view of a rail-joint constructed in accordance with this invention. Fig. 2 is a transverse sectional view of the same. Fig. 3 is a side elevation. Fig. 4 is a perspective view showing the rail chair, with the rails and key removed. Fig. 5 is a side elevation of the joint, partly in section.

Referring to the drawings A and B designate the ends of the pair of rails forming a joint, which are seated in a chair 1. The chair is provided with sides 2 and 3, the side 3 being cut away as at 4, to provide for a removable key 7. The side 2 is provided with

35 a projection 5 which engages a recess 6 in one end of the rail.

When the parts are assembled the key 7 is removed and rail A is inserted and then the key 7 is arranged in its proper place thus forming a complete joint. When it is desired to take the joint apart the coiled end 8 of the key 7 is driven outwardly until the same is removed when the parts can be readily disassembled as will be readily understood.

40 A portion of the chair is provided with an extension 9 which is bent upon itself as at 10 thus forming a clamp for engaging the lower portion 11 of the key 7. If desired the key may be locked in position by means of a 50 spike 12. The under side of the chair is provided with a flange 13 for strengthening the joint.

45 What is claimed is:

A device of the class described comprising 55 the abutting ends of rails mounted in a shoe 1, said shoe having sides 2 and 3, the side 2 being provided with an inward projection 5 adapted to engage a recess in one of the rails, the side 3 being cut away at one end, the 60 base portion of said shoe having an extension formed in a loop, and a key adapted to engage said loop and the inner face of the side 3 whereby the several parts are securely locked in their assembled position.

65 In testimony whereof I have signed my name to this specification in the presence of two subscribing witnesses.

GOMER LEWIS.
